CLAIM

We claim the ornamental design for an electronic stereo sound generating device, as shown and described.

DESCRIPTION

FIG. 1 is a perspective front view of an electronic stereo sound generating device, showing our new design; FIG. 2 is a rear perspective view of the invention of FIG. 1; FIG. 3 is a front view of the invention of FIG. 1; FIG. 4 is a top plan view of the invention of FIG. 1; FIG. 5 is a rear view of the invention of FIG. 1; FIG. 6 is bottom plan view of the invention of FIG. 1; FIG. 7 is a right side elevation of the invention of FIG. 1; and, FIG. 8 is a left side elevation view of the invention of FIG. 1.
